UNITED STATES PATENT OFFICE.

THOMAS JOSEPH BARRETT, OF WASHINGTON CROSSING, PENNSYLVANIA.

PAVEMENT INSERT.

Application filed October 4, 1927. Serial No. 223,933.

The invention relates to pavement inserts and has as an object the provision of a structure which may be imbedded in pavements to provide tracks for wheels, expansion joint protectors, or signals in the form of lines to divide traffic flowing in opposite directions or letters to give warnings as "stop" signs, and and as a reinforced paving brick.

It is a further object of the invention to provide metal reinforced means which may be imbedded in the surface of a pavement to provide areas of increased resistance to wear.

It is a further object of the invention to provide inserts which may be placed over expansion joints to provide increased resistance to wear to the edges of the joints and which are slightly compressible to allow for expansion of the pavement at each side of the joint.

It is a further object of the invention to provide inserts for pavements which may if desired be joined together to protect an extended area of pavement.

It is a further object of the invention to provide inserts for pavements which have a different appearance from the remainder of the pavement and which therefore may serve as signals either in the form of a dividing line to separate oppositely moving traffic or in the form of letters to indicate a warning as a "stop" sign.

It is a further object of the invention to provide a metal insert which comprises a body of initially plastic material as an asphalt and sand mixture having metallic elements to prevent the plastic from pushing into waves and having portions of the metal extending to the surface to reduce wear.

It is a further object of the invention to provide a method of uniting plastic pre-formed elements in a pavement.

Further objects of the invention will appear from the following description when read in connection with the accompanying drawings showing illustrative embodiments of the invention and wherein:

Figure 1 is a perspective view partly in section;

Fig. 2 is a plan view of the metallic elements provided by the invention;

Fig. 3 is a vertical section on line 3-3 of Fig. 2;

Fig. 4 is a detail plan view of a modified form of metallic elements;

Fig. 5 is a detail perspective view partly in

section showing one form of the metallic elements providing compressibility;

Fig. 6 is a view similar to Figure 5 showing a modified form of compressible metallic element;

Fig. 7 is a detail plan view of the metallic elements of Fig. 5; and

Fig. 8 is a plan view of the metallic elements of a series of letters.

As shown in Figure 1, a pavement is provided preferably of concrete 10 having inserts 11 providing wheel tracks for vehicles, the concrete being formed with a longitudinal expansion joint 12 protected by an insert 13 acting as an expansion joint filler and as a signal line to separate oppositely moving traffic. The insert shown at 13 may be utilized in the place of the usual lines painted upon pavements notably at curves.

As shown in Figures 2 and 3, the metal insert is in the form of bars 14 placed on edge 75 and united by vertical bars 15, 16, desirably electrically welded to the lower edges of bars 14. The bars 14 are shown as provided with recesses 17 which are located in staggered relation in successive bars.

The metallic elements of Figures 2 and 3 after assembly may be surrounded by plastic material such as a sand-asphalt mixture coming flush with the top of bars 14 between the recesses 17 and flowing through the recesses 85 submerging the bars in the recesses as indicated in connection with the tracks 11 of Figure 1.

When it is desired to make up an extended surface of paving by means of the inserts 11 running longitudinally, the ends of the bars 14 are given a complementary V-shape formation as indicated at 18, 19, and running longitudinally of the road the plastic material of each insert is made flush with the complementary V-shape formation so that the blocks may be interlocked as shown by Figure 3. When it is desired to place a series of such inserts in union in a pavement, the V-shaped projection and grooves in the edges of the blocks are 100 painted with a material such as asphalt cut-back with an inflammable solvent such as gasoline and in the process of placing the blocks the cutback material is ignited to burn out the solvent and heat the edges of the inserts which are thus welded together when pressed into contact. The presence of the plastic material in which the inserts are im-

bedded and which forms a portion of the inserts provides a cushion below the edges of the bars 14 and the staggered relation of the recesses 17 will prevent the flowing of the material into waves under the influence of traffic while the metallic projections between the recesses 17 appearing at the surface will act as wear-resistant elements.

The form of expansion joint filler and signal line shown at 13 is formed with the bars 14' extending longitudinally and the bars 15' placed at intervals beneath the bars 14'. It may also be used with a concave surface at short turns, to hold and regulate traffic and when reinforced may be made flat for use of markers and the like at intersections of the street.

The bars 15 are shown as projecting beyond the outer elements 14' whereby they may become imbedded in the concrete as indicated at 20, Figure 1, to retain the insert in position and to serve as dowel pins to preserve the vertical relation between the edges of the blocks upon each side of expansion joint 12. The above method may be used in tracks, when bars as shown in Figure 3 are laid longitudinally.

In this form of expansion joint the bars 14' are desirably made of different widths so as to provide a bead with an upwardly curved surface over the expansion joint and being of a different appearance from the concrete on each side thereof may be used to replace the usual painted line to divide oppositely moving traffic.

The form of the invention shown in Figures 5, 6 and 7 may be utilized upon transverse expansion joints and is shown formed with a flat surface to offer no resistance to wheels passing thereover. In the form of Figure 5 the transverse bars 21 are shown as provided with a slip joint 22 thereby allowing for compressibility of the insert and in this form of the invention also the bars 21 are shown as projecting laterally beyond the outer bars 14 to anchor the insert in the concrete and to serve as dowel pins as already described.

As shown in Figure 6, the bars 23 are formed with inherent compressibility by virtue of the deformation of the bars to provide portions 24 projecting at one side of the bars and forming recesses 25 in the remaining edge of the bars to provide longitudinal flexibility thereof.

It is to be understood that the bars 21 and 23 are welded to the bars 14 at the lower edges thereof as in the form already described in Figures 1 to 4 inclusive and are imbedded in the plastic material as sand asphalt mixture 26 as in the form first described.

In the form of the invention shown in Figure 8 the inserts are given the form of letters formed of bars 27 placed on edge and having the bars 28 placed below the same and weld-

ed thereto to preserve the assembly and to provide the cushion of plastic material under the bars 27, which plastic material is formed flush with the lower edges of the bars 28.

In forming the letter T shown in Figure 8 one of the bars as 28' is given a U-shape formation to connect the vertical and transverse bars 27 to form the top of the letter and certain of the bars 27 may also be bent to an angle as shown at 27' to provide additional connection between the members of the letter. In the case of the letter P also one of the bars 28 is shown with an L form at 29 and one of the bars 27 is also shown at 30 to be integral in the vertical and transversely extending portion of the letter. The bars 27 of the letters are desirably formed with the recesses 17 after the manner indicated in Figures 1 to 3 inclusive, 5, 6, and 7.

The inserts provided by the invention may be assembled at a factory with the asphalt mixture combined therewith and thus preformed may be shipped to the field and imbedded in the pavement during the laying thereof.

The presence of the metal projections in the surface of the inserts providing a surface of differing characteristics will have valuable anti-slip qualities as well as a greater resistance to wear.

Minor changes may be made in the physical embodiment of the invention within the scope of the appended claims without departing from the spirit thereof.

I claim:

1. A preformed reinforced bituminous pavement insert comprising, in combination, a plurality of spaced, substantially parallel bars placed on edge, a plurality of spaced bars extending below and transversely of said first named bars and rigidly secured to the edges thereof, and a body of bituminous material filling the spaces between said first named bars, terminating flush with the upper edges thereof and extending below the lower edges thereof.

2. A preformed reinforced bituminous pavement insert comprising, in combination, a plurality of spaced, substantially parallel bars placed on edge, a plurality of spaced bars extending below and transversely of said first named bars rigidly secured to the edges thereof and having their ends projecting beyond the outer thereof to anchor in a pavement, and a body of bituminous material filling the spaces between said first named bars, terminating flush with the upper edges thereof and extending below the lower edges thereof.

3. A preformed reinforced bituminous pavement insert comprising, in combination, a plurality of substantially parallel spaced bars placed on edge, a plurality of spaced bars extending below and transversely of

said first named bars and rigidly secured to the edges thereof, said last named bars provided with formations movable relative to each other under influence of the expansion 5 and contraction of a pavement, and a body of bituminous material filling the spaces between said bars, terminating flush with the upper edges of the first named bars and extending below the lower edges thereof, 10 whereby to provide a cover for an expansion joint in a pavement.

4. A preformed reinforced bituminous pavement insert comprising, in combination, a plurality of substantially parallel spaced

bars placed on edge and extending longitudinally of the insert, said bars progressively increasing in width toward the longitudinal center of the insert and having their lower edges substantially in a common plane, a plurality of spaced bars extending below 20 and transversely of said first named bars and rigidly secured to the edges thereof and a body of bituminous material filling the spaces between said bars, terminating flush with the upper edges and extending below 25 the lower edges of said first named bars.

THOMAS JOSEPH BARRETT.
